(57) **CLAIM**

The ornamental design for a flux applicator, as shown and described.

DESCRIPTION

FIG. 1 is a side view of a flux applicator, showing our new design;

FIG. 2 is a front perspective view thereof;

FIG. 3 is a bottom view thereof;

FIG. 4 is a top view thereof;

FIG. 5 is a front view thereof; and,

FIG. 6 is a rear view thereof.

The broken lines in the figures illustrate the portions of the design that form no part of the claimed design.
